UNITED STATES PATENT OFFICE.

JESSE CLEMENTS, OF NORTHFLEET, ENGLAND.

SHUTTERING DEVICE FOR CASTING WALLS.

Application filed November 21, 1925. Serial No. 70,701.

This invention relates to improvements in shuttering devices for building concrete walls in situ in which the shuttering boards or the like are spaced, positioned and kept in place by a plurality of vertically arranged supports which can be successively advanced as the work progresses, and it has for its object a form of supporting unit which can be selectively and continuously utilized for building both cavity and solid walls of different thicknesses. Another object of this invention is to enable a maximum height of wall to be built before a new adjustment of the shuttering devices is necessary. A further object is the provision of means for securing the vertical supports to the transverse members and for enabling said vertical members to have transverse movement relative to the transverse members in order to free the vertical members from the shuttering boards without disturbing the wall. A still further object is to facilitate the release and withdrawal of the inside shuttering boards in building cavity walls.

I attain these objects by the construction illustrated in the accompanying drawings which illustrate a construction of the device which can be used for building solid walls of four different thicknesses and cavity walls of two different thicknesses. In these drawings Figures 1 and 2 are views in plan and elevation of one of the cross plates of a supporting unit suitable for supporting the shuttering boards for casting cavity walls of $13\frac{1}{2}$ inches and 18 inches thickness, and solid walls of $4\frac{1}{2}$ inches, 9 inches, $13\frac{1}{2}$ inches, and 18 inches thickness. Figure 3 is a view in cross section of one of the supports, Figure 4 is a view in cross section of another of the supports, Figures 5 and 6 are views in elevation and in plan showing the use and application of the improved supporting unit in casting a $13\frac{1}{2}$ inch cavity wall. Figure 7 is a similar broken view showing it when casting an 18 inch cavity wall. Figures 8, 9, 10 and 11 are similar broken views showing the device employed for casting solid walls of $4\frac{1}{2}$, 9, $13\frac{1}{2}$ and 18 inches respectively.

Throughout the views similar parts are marked with like numerals of reference.

The shutter supporting units each consist of a plurality of flat plates 1, three rods 2, 3 and 4, and a plurality of wedges 5. The

rods are for convenience all of uniform or approximately uniform length and as far as possible of the same width and thickness.

In each of the plates 1 are four apertures 6, 7, 8 and 9, the first and second of which are located at the ends of the plate and the aperture 8 is located at a predetermined distance from one of the end apertures. The width of each of these apertures is slightly in excess of the thickness of the rods 2, 3, and 4, so that they can pass freely through said apertures and the length of said apertures exceeds the width of said rods to the extent necessary to receive the wedges 5 and to allow the rods to come free of the shuttering boards when the wedges are withdrawn.

The other aperture 9 which is located between the aperture 8 and one of the end apertures 6 or 7 is of approximately the same length as the other apertures and its width is approximately the same as its length for a purpose that will hereinafter be apparent.

In the construction illustrated in the accompanying drawings the distance between the aperture 9 and the aperture 6 is $4\frac{1}{2}$ inches plus the thickness of two of the shuttering boards 10, the distance between the aperture 9 and the aperture 7 is 9 inches plus the thickness of two shuttering boards, and the distance between the aperture 8 and the aperture 6 is $13\frac{1}{2}$ inches plus the thickness of two shuttering boards.

For casting solid walls $4\frac{1}{2}$, 9, $13\frac{1}{2}$ or 18 inches thick two rods 2 and 3 are employed which engage respectively the apertures 6 and 9, 6 and 8 or 6 and 7 in the plates 1. For casting cavity walls $13\frac{1}{2}$ or 18 inches thick three rods 2, 3 and 4, are employed which engage respectively with the apertures 6, 8 and 9 or 6, 7 and 9.

In operation the plates 1 are allowed to remain in the wall to support the rods and as the work proceeds said rods are raised vertically step by step according to the distance apart the plates 1 are spaced and as said plates are no longer required they are knocked out of the wall before the concrete has set.

In building cavity walls the rod 4 is only locked to the upper plate 1 and in order to release the inside shuttering the rod, after the wedges have been withdrawn, is turned through an angle of 90° as shown in dotted

lines in Figure 6 so as to bring its width transverse to the plate. This frees it from the shuttering boards and allows it to be readily withdrawn after which the shuttering boards can be lifted out one by one either directly by hand or by the use of a hooked rod.

It will be understood that in constructing cavity walls the width of the cavity can within the limits be determined either by the width of the bar employed to engage the apertures 9 in the plates or by the thickness of the shuttering boards employed or by both in combination. Beyond these limits one or more additional apertures 9 must be provided.

What I claim is:—

1. A shuttering device for building concrete walls in situ comprising three bars and a plurality of bracing plates each of which has three or more apertures through which the bars pass, one of said bars having a width greater than its thickness, and one of the apertures in said plate—with which said bar coacts—having a length slightly in excess of the width of said bar and a width approximately equal to its length, the other bars being of any suitable section and the other apertures in each of the plates being slightly larger than said bars, and wedges for engaging the bars in the apertures in the plates so as to lock said bars and plates together.

2. A shuttering device for building concrete walls in situ comprising three bars and a plurality of bracing plates each of which has three or more apertures through which the bars pass, one of said bars having a width greater than its thickness, and one of the apertures in said plate with which said bar coacts being located between two of said other apertures and having a length slightly in excess of the width of said bar and a width approximately equal to its length, the other bars being of any suitable section and the other apertures in each of the plates being slightly larger than said bars, and wedges for engaging the bars in the apertures in the plates so as to lock said bars and plates together.

3. A shuttering device for building concrete walls in situ comprising three bars and a plurality of bracing plates each of which has three or more apertures through which the bars pass, one of said bars having a width greater than its thickness, and one of the apertures in said plate with which said bar coacts being located between one of the other apertures at one end of the plate and one of the other apertures therein and having a length slightly in excess of the width of said bar and a width approximately equal to its length, the other bars being of any suitable section and the other apertures in each of the plates being slightly

larger than said bars, and wedges for engaging the bars in the apertures in the plates so as to lock said bars and plates together.

4. A device for supporting the shuttering boards employed for building solid or cavity concrete walls in situ comprising three bars two of which engage the shuttering boards which determine the outer faces of the wall, and the other of which engages the shuttering boards which determine the faces of the cavity in the wall, plates for positioning said bars each having three or more holes by which said plates can be passed over said bars and the positions of the shuttering boards be located to build the type and size of wall desired, and wedges engaging the apertures in the plates in such a manner as to bind the plates to the bars.

5. Shuttering for casting walls in situ comprising a series of boards piled on edge, a plurality of rods adapted to position said boards said rods being all of equal width and thickness the width being in excess of the thickness, a plurality of plates each having three apertures to receive the rods the aperture intermediate to two of said other apertures having a length slightly in excess of the width of the rods and a width approximately the same as its length and the other of said apertures having a length slightly in excess of the width of the rods and a width slightly in excess of the thickness of said rods; and a plurality of wedges adapted to cooperate with the apertures of said plates and with said rods both for the purpose of securing said rods to said plates and for allowing relative transverse movement between said rods and said plates when the wedges are removed.

6. Shuttering irons for positioning and securing the shutters employed for casting walls in situ each comprising a plurality of rods adapted to engage the shuttering, a plurality of plates adapted to be placed transversely to the wall each having a plurality of apertures to receive said rods, two of said apertures defining the exterior faces of the wall and one of said apertures defining both of the cavity in the wall, and a plurality of wedges for securing the bars and plates to one another and for enabling the bars to have transverse movement relative to the plates when the wedges are removed.

7. A shuttering device for building concrete walls in situ comprising a plurality of rectangular bars for supporting and positioning the shuttering boards, a series of plates each having four apertures through which the bars can pass and which determine the thickness and type of wall to be built, all of said apertures being large enough for the bars to pass through them and one of said apertures being large enough

to allow the bar passing through it to be turned through an angle of 90°, and wedges for locking said plates and bars together.

8. A shuttering device for building concrete walls in situ comprising three bars of rectangular shape in cross section, a series of plates each having four holes all of said holes being large enough to allow the plates to be passed over said bars, and the other of said holes—which is located between two of the other holes—being large enough to allow the bar engaging with it to be turned through an angle of 90°, and wedges coacting with and between the bars and the plates for the purpose of locking them together.

9. A shuttering device for building concrete walls in situ comprising three bars of rectangular shape in cross section, a series 20 of plates each having four holes all of said holes being large enough to allow the plates to be passed over the bars and the other of said holes—which is located between one of the other holes at one end of the plate and 25 one of the other holes—being large enough to allow the bar engaging with it to be turned through an angle of 90°, and wedges coacting with and between the bars and the plates for the purpose of fixing them to 30 one another.

10. A device for supporting the shuttering employed for building concrete walls in situ, comprising three bars of equal width and

thickness the width being greater than the thickness, a plurality of plates each having 35 four apertures to receive said bars, one of said apertures intermediate to two of said other apertures having a length slightly in excess of the width of the bars and a width approximately the same as its length, and 40 the other of said apertures having a length slightly in excess of the width of the bars and a width slightly in excess of the thickness of said bars, and a plurality of wedges 45 adapted to engage said apertures so as to secure said bars to said plates.

11. A device for supporting the shuttering employed for building concrete walls in situ, comprising three bars of equal width and thickness the width being greater than 50 the thickness, a plurality of plates each having four apertures to receive said bars, one of said apertures which is located between one of the end apertures in the plate and one of the other apertures therein having a 55 length slightly in excess of the width of the bars and a width approximately the same as its length, and the other of said apertures having a length slightly in excess of the width of the bars and a width slightly in 60 excess of the thickness of said bars, and a plurality of wedges adapted to engage said apertures so as to secure said bars to said plates.

JESSE CLEMENTS.
